FREEZING, HARDENING, AND DISPENSING
CABINET AND CONTAINERS THEREFOR

Louis A. M. Phelan, Beloit, Wis.

Original application July 27, 1940, Serial No. 347,830. Divided and this application September 25, 1944, Serial No. 555,702

3 Claims. (Cl. 62—99)

1

This application is a divisional of my copending application, Serial No. 347,830, filed July 27, 1940, now Patent No. 2,361,649, issued October 31, 1944.

The present invention relates to a novel hardening and dispensing cabinet in combination with a counter freezer.

An object of the present invention is to provide a cabinet with three compartments, number one compartment occupying the full depth of the interior of the cabinet and extending from one end of the cabinet preferably past the longitudinal center thereof, numbers two and three compartments being positioned one above the other and occupying the remainder of the length of the interior of the cabinet. Number two compartment is adapted to contain a compressor unit and number three compartment is adapted to receive containers.

A novel feature of my invention is a permanent insulated covering adapted to lie over a portion of the number one and three compartments providing a support for a counter freezer and without reducing the useful area of these compartments.

A further object of my invention is to provide evaporator coils in the first compartment and optionally evaporator coils in the third compartment, whereby containers containing ice cream and the like may be placed in the first compartment and served therefrom and whereby the third compartment may be similarly used or used for other purposes.

A further object of the present invention is to provide operating connections between the counter freezer evaporator and the first compartment evaporator, with means whereby these evaporators may be served by the single compressor unit, and whereby the temperature in the third compartment may be adapted for frozen product or for storing fresh mixes, either by heat exchange between the first and third compartments or by the use of a separate evaporator.

Generally stated, objects of the present invention are to provide a single unit adapted for freezing, storing, hardening and serving ice cream and the like in the most economical manner.

To these and other useful ends, my invention consists of parts, combinations of parts or their equivalents and mode of operation as hereinafter set forth and claimed and shown in the accompanying drawings in which:

Fig. 1 is a perspective view of the preferred form of my invention.

2

Fig. 2 is a top view of the device as illustrated in Figure 1.

Fig. 3 is a horizontal sectional view of the device taken on line 3—3 of Figure 4 omitting the containers in compartment three.

Fig. 4 is a vertical longitudinal section of the cabinet taken largely on line 4—4 of Figure 3, a front view of the counter freezer being shown.

Fig. 5 is a sectional view taken on line 5—5 of Figure 4.

Fig. 6 illustrates one of the evaporator slabs partially sectioned.

Fig. 7 is a sectional view taken on line 7—7 of Figure 6.

Fig. 8 is an enlarged fractional portion of the slab shown in Figure 6 and sectioned on line 4—4 of Figure 6.

I have evolved the present device having in mind the most convenient apparatus for use in a confectionery store wherein ice cream and the like is primarily frozen by means of the counter freezer which is mounted on the top of the cabinet as will hereinafter appear.

I have illustrated the compartments in the cabinet shown and identified them by numerals 1, 2 and 3, each being especially suited for the purpose specified. It will be understood that compartments 1 and 3 are suitable for the reception and storage of any desired shape of containers.

Cabinets of the character are generally positioned in a delicatessen store frequently taking the place of a counter. Therefore the space occupied is very important and I have therefore especially designed my device for this purpose.

In the drawings I have identified the counter freezer in its entirety by reference character D and the cabinet in its entirety by reference character E. Member D has an evaporator and mixing chamber which is preferably similar to my Patent #2,243,317, May 24, 1941. The shape of the containers shown in compartment 1 is preferable and they are designated in their entireties by reference character A and the containers shown in compartment 3 are designated by reference character B. The compressor unit is in its entirety designated by reference character C.

Member E is preferably shaped as illustrated, having side members 13—13 and end members 14—14. Compartment 1 is adapted to receive containers of any desirable shape preferably however as shown in the figures, the sides, end and bottom of this compartment being insulated as shown. Compartment 2 need not be insulated on its sides, end and bottom and is shaped and

positioned preferably as shown in the figures. Compartment 3 is positioned over compartment 2 and insulated therefrom as shown at 15. Compartment 1 is insulated from compartments 2 and 3 preferably as at 16. Under some circumstances the temperature of compartment 3 may be controlled by leaving out the partition between compartments 1 and 3 or compartments 1 and 3 may be separated only by a metal partition. Thus compartment 3 would be cooled by the evaporators in compartment 1; however evaporator coils may be suitably placed in compartment 3.

I provide a transverse insulated covering 18 which overhangs partition 16 and acts as a support for member D. The remainder of the tops of compartments 1 and 3 are covered by insulated lids 19—19 and 20—20.

Compartment 2 is provided with an entrance door or lid preferably as at 25. I provide suitable ventilator grilles (not shown) for compartment 2. I mount in this compartment compressor unit C having a condenser 26 and inlet and outlet pipes 27 and 28 which are operatively connected to the evaporator coils in compartment 1 and to the evaporator chamber in member D, partly shown by dotted lines.

I will now describe my preferred form of evaporators for chamber 1 comprising evaporator slabs designated in their entireties by reference characters F and G each having therein evaporator coils 29 which are operatively connected to compressor pipes 27 and 28.

Slabs F are adapted to form the side walls of chamber 1, comprising a pan 35 having therein evaporator coils 29 which are preferably positioned as shown in Figure 6. These coils 29 are preferably bonded to the bottom of the pan 35 after which the pans are filled by a suitable molten insulating material 36; thus the evaporator tubes are in heat exchange with the side walls of compartment 1. Slab G differs somewhat from slab F in that it is provided with a metal lid 38 so member G is suitable to be positioned in the center of compartment 1 as shown in Figure 5. Thus if the containers A are arranged in two rows in compartment 1, two sides are positioned close to the evaporator slabs, thus to provide a uniform heat transfer for the contents of the containers A. During the assembling of my cabinet, slabs F are positioned as shown in Figure 5 so as to form the inner side walls of compartment 1. Then metal partitions 39—39 and bottom plate 40 are secured together and connected to slab members 35 so as to complete compartment 1. I preferably position a number of spaced wood pieces 41 under partition 40 as a support for this member.

Compartment 3 is formed from sheet metal into a rectangular chamber and positioned as illustrated in Figures 3 and 4. The upper edges of members 39, F, and 42 terminate on the same horizontal plane and act as a support for transverse wood blocks 43 and member 18, after which the space around and under chambers 1 and 3 are filled with suitably insulated material 46. I provide special insulating material 47 which acts as a covering for insulating material 46. This material extends slightly above the top surfaces of members 43 and while it is still hot I press a top sheet 47 of preferably stainless steel into position, having openings for compartments 1 and 3 and a top cover for partition 18. Thus when slab G is in position, the three slabs may be operatively connected to compressor unit

pipes 27 and 28, these pipes extending through partition 40 for the purpose.

Pipes 27 and 28 are also operatively connected to the evaporator of unit D by means of other pipes 49 and 50 (shown by dotted lines) whereby the slabs F and G and the evaporator chamber of member D may be served by compressor unit C. Controlling mechanisms (not shown) are furnished whereby these members may be served by the compressor unit automatically or under manual control.

Thus it will be seen that I have provided two compartments for containers and storage; that the control of the temperature in the container compartments may be automatic or manual; that the compressor may supply refrigerant to the counter freezer evaporator, as well as to compartment 1 evaporator; that the store clerk may at liberty, use compartment 3 for frozen and hardened product from which to serve; that the freezing, hardening and dispensing operations are conveniently handled and economical and that the cabinet will occupy minimum floor space.

Having thus shown and described my invention I claim:

1. A device of the character described comprising in combination, a counter freezer, a horizontally elongated hardening and dispensing cabinet, a compartment rectangular in horizontal and longitudinal cross section occupying a space in the cabinet extending from one end past the longitudinal center of the cabinet and being adapted for the reception of containers, a second compartment at the bottom of the other end of said cabinet and being separated from the first compartment by means of an insulated partition, a compressor unit in said second compartment, evaporator coils operatively connected to said compressor unit and positioned in heat exchange contact with said first compartment, a third compartment positioned above said second compartment and having substantially the same horizontal length and width as the second compartment and being surrounded horizontally by insulated walls and having an insulated bottom, a transverse permanent insulated covering on the top of said cabinet and extending a short distance longitudinally of said cabinet over said first and third compartments, said counter freezer being mounted on said transverse covering and having an operating connection with said compressor unit, insulated removable lids forming coverings for the remainder of the tops of said first and third compartments, the remainder of said first compartment being insulated from the exterior.

2. A device of the character described comprising in combination, a counter freezer, a generally horizontally elongated hardening and dispensing cabinet, a compartment occupying a space in the cabinet extending from one end past the longitudinal center of the cabinet and being adapted for the reception of containers, a second compartment at the bottom of the other end of said cabinet and being separated from the first compartment by means of an insulated partition, a compressor unit in said second compartment, evaporator coils operatively connected with said compressor unit and positioned in heat exchange contact with said first compartment, a third compartment positioned above said second compartment and having substantially the same horizontal length and width as the second compartment and being separated from said first compartment by a partition and from the second

compartment by an insulated partition, a transverse permanent insulated covering on the top of said cabinet and extending a short distance longitudinally over said first and third compartments, said counter freezer being mounted on said transverse covering and having an operating connection with said compressor unit, removable insulated lids forming coverings for the remainder of the tops of said first and third compartments, the remainder of said first and third compartments being insulated from the exterior.

3. A device of the character described comprising in combination, a counter freezer, a generally horizontally elongated hardening and dispensing cabinet, a compartment generally rectangular in horizontal and longitudinal cross section occupying a space in the cabinet and extending from one end to near the longitudinal center of the cabinet and being adapted for the reception of frozen product containers, a second compartment between the inner end of the first compartment and the other end of the cabinet and being separated from the first compartment by an insulated partition, a compressor unit in said second compartment, evaporator coils in heat exchange contact with said first compartment and having an operating connection with said compressor unit, a third compartment positioned over said

second compartment and having substantially the same horizontal length and width as the second compartment and being separated from the second compartment by an insulated partition, a permanent transverse insulated covering positioned to cover a portion of the adjacent ends of said first and third compartments, said counter freezer being positioned on said transverse covering and having an operating connection with said compressor unit, removable insulated lids adapted to cover the remainder of said first and third compartments, the remainder of said first and third compartments being insulated from the exterior.
